UNITED STATES PATENT OFFICE

WILLIAM H. PETIT AND EDSON S. HINELINE, OF ROCHESTER, NEW YORK

DESIGN FOR A CAMERA CASING

Application filed January 25, 1933. Serial No. 46,991. Term of patent 14 years.

To all whom it may concern:

Be it known that we, WILLIAM H. PETT and EDSON S. HINELINE, citizens of the United States, and residents of Rochester, in the county of Monroe and State of New York, have invented a new, original, and ornamental Design for a Camera Casing, of which the following is a specification, reference being had to the accompanying drawings, forming a part thereof.

In the drawings:

Fig. 1 is a front elevation of a camera casing showing our new design, the cover and hood thereof being open;

Fig. 2 is an end view of the camera casing in open position; and Fig. 3 is a front perspective view of the camera casing in closed position.

We claim:

The ornamental design for a camera casing, as shown and described.

In testimony whereof, we have signed our names to this specification.

WILLIAM H. PETIT.
EDSON S. HINELINE.
